FRANK L. NORTON,
by James L. Hopkins, ATTORNEY.

UNITED STATES PATENT OFFICE.

FRANK L. NORTON, OF ST. LOUIS, MISSOURI.

CONCRETE MIXING AND DISTRIBUTING APPARATUS.

1,410,030.

Specification of Letters Patent. Patented Mar. 21, 1922.

Application filed April 2, 1920. Serial No. 370,674.

To all whom it may concern:

Be it known that I, FRANK L. NORTON, a citizen of the United States, residing at St. Louis, State of Missouri, have invented certain new and useful Improvements in Concrete Mixing and Distributing Apparatus, of which the following is a specification, reference being had therein to the accompanying drawing.

10 My invention relates to improvements in concrete mixing and distributing apparatus and has for its object to provide a mechanism whereby concrete is mixed and elevated in a rotating receptacle and discharged therefrom at the highest point to which the receptacle is lifted, into a distributing trough.

In the drawings—

Fig. 1 is a side elevation of an apparatus embodying my invention.

20 Fig. 2 is a diagrammatic view of the drum or receptacle employed therein showing its lid or closure in opened position.

Fig. 3 is a like view of the same with the lid in closed position.

25 Fig. 4 is a like view of the same illustrating the closure open and in position to discharge its contents.

Fig. 5 is a longitudinal vertical view of a fragment of one end of one of the mixing drums employed in the machine of my invention.

30 Fig. 6 is a top plan view of one of said drums.

Fig. 7 is an end view of the cover of one of 35 said drums.

Fig. 8 is a perspective view of one of the pins wherewith the cover-latch engages.

Fig. 9 is a top plan view illustrating the baffles employed in said drums.

40 I employ a frame comprising standards 6 and 7, joined at their tops by the cross-arm 8 and connected by the brace 9 (carrying the distributing trough 10) and the beam 11, on which the arm 12 is mounted by means of the 45 hinge 13.

I employ two drums, 14 and 15, on the opposite sides of the frame, each having a sprocket-wheel 16 engaging with the chain 17, one end of which chain 17 is secured to 50 the standard 6 at the point indicated as 18, the other end at 19 to the standard 7. The drums 14 and 15 are so disposed, and the chain 17 is so carried by the sprocket wheels 20 and 21 mounted on the upper part of the 55 frame that the drum 15 is at the bottom of

its path of travel when the drum 14 is at its topmost position, as shown in Fig. 1.

Each of said drums 14 and 15 has a cover 22 provided at each end with a flange 23 which is seated in the recess 24 (formed between the circular head 25 and interior head 26 of the drum as shown in Fig. 5) when the cover 22 is in the closed position indicated in Fig. 3.

Pins 27 are mounted in the drum ends, 65 and project within the drum, and are formed as shown in Fig. 8, having a rounded head 28 beneath which both sides are cut away to form the grooves 29. Upon the upper face of the cover 22 are latches 30—30 70 having circular apertures 31 which admit the heads 28 of the pins 27, slots 32 extending rearwardly from said apertures 31 and being dimensioned to engage the grooves 29—29 of the pins 27. Each latch 30 is held 75 to the cover 22 by a clamp 33, which is riveted to the cover and has its rear portion upturned to form the terminal 34.

A cross-bar 35 connects the upper ends of the levers 36—36, which terminate in forks 80 37 and are fulcrumed on the pins 38 held in bearings 38^a secured to the cover. The cover 22 is unlatched by a forward movement of the cross-bar 35 and locked by its reverse movement, as illustrated in Figs. 6 and 7. 85

The cover 22 is provided with the pivoted locking bar 39 whose indentations 40 and 41 engage with a pin 42 when the cover 22 is in fully or partly opened position as shown in Figs. 2 and 4; the bar 39 hanging idle 90 when the cover 22 is in closed position, as shown in Fig. 3.

In the interior of each drum I provide one radially-disposed partition 43 extending from end to end of the drum's interior and 95 from its axis to its bottom. Transversely above said partition 43 the baffles 44 are mounted, as shown in Figs. 2 and 9.

The cover 22 has a handle 55 which is so located that it will be grasped together with the cross-bar 35 by the hand of the operator when the cover 22 is in unlatched position and it is desired to open it.

This opening is effected when the drum 15 is in its lowest position, as shown in Fig. 1. The drum 15 is then supplied with a charge of concrete, and the cover 22 closed and latched by hand. The crank 45 is then operated to raise the drum 15 and lower the drum 14. When the drum 15 has ascended 110

to a point in alinement with the end of the unlocking bar 46, the roller 47 mounted on said bar 46 will contact with the guide 48 and the continued rotation of the drum 15 will bring the bar 46 into contact with the lever 36, forcing said lever outwardly to unlatch the cover 22 which will, upon the further revolution of said drum, drop by gravity into the opened and discharging position illustrated in Fig. 4 and at the left-hand side of Fig. 1, in which position its contents will be liberated, and discharged by their own weight into the trough 10.

A corresponding unlocking bar 48 with a roller 49 serves to unlock the drum 14 as shown in Fig. 1. A stop 50 serves to limit the downward movement of the unlocking bars 46 and 48. In the descending course of the drums 14 and 15, when empty, the bars 46 and 48 serve to again latch their covers.

As shown in the drawings the lid or cover 22 is provided with a practically water-tight hinge construction. The lid 22 has its rear edge convexed as indicated by 51, to register with a longitudinal flange or corrugation 52 in the edge of the outer wall 53 of the drum. The hinge 54 being secured to the outer face of the lid 22, the flange 52 serves, when the lid 22 is in the opened position shown in Fig. 2, to prevent any leakage of the drum-

content at the hinge-line, while said drum-content is being discharged.

The baffles 44 are arranged parallel with each other and at an angle to the partition 43, and as shown in Fig. 9 extend entirely across the interior of the drum.

Having thus described my invention, what I claim and desire to have secured to me by the grant of Letters Patent is—

1. In a device of the class described, in combination, a vertical frame; a pair of drums mounted upon opposite sides of said frame; means for alternately raising and lowering each of said drums; and means comprising arms hingedly mounted on the frame and pivoted locking bars on the drums arranged to contact with said arms for opening each drum when in raised position to liberate its contents.

2. In a device of the class described a drum having a radially disposed partition extending from end to end of the interior of the drum and from its axis to its bottom; and a series of baffles extending across the interior of said drum above said partition and arranged parallel to each other and at an angle to said partition.

In testimony whereof I hereunto affix my signature.

FRANK L. NORTON.
